W. A. PRENTISS

MEANS FOR ATTACHING LABELS TO SPOOLS OR OTHER ARTICLES

Filed April 28, 1923

INVENTOR.
William A. Prentiss.

BY
Harry M. Brown.
ATTORNEY.

UNITED STATES PATENT OFFICE.

WILLIAM A. PRENTISS, OF HOLYOKE, MASSACHUSETTS.

MEANS FOR ATTACHING LABELS TO SPOOLS OR OTHER ARTICLES.

Application filed April 28, 1923. Serial No. 635,342.

To all whom it may concern:

Be it known that I, WILLIAM A. PRENTISS, a citizen of the United States of America, residing at Holyoke, county of Hampden, 5 Commonwealth of Massachusetts, have invented certain new and useful Improvements in Means for Attaching Labels to Spools or Other Articles, of which the following is a specification.

- 10 This invention relates to improvements in devices for attaching a label as to the head or spool end of spools, preferably metal spools which are designed for winding wire or other material thereon.
- 15 Heretofore, the usual practice has been to attach the label by pasting a piece of paper or cardboard onto the ends of the spool heads. This has been found to be objectionable, since the labels soon become soiled and 20 detached. The pasting of labels on articles made of various materials, such as wood or metal, is often undesirable since as the paste dries the label often becomes displaced and lost.
- 25 The present invention broadly comprises a label member which is formed of paper, cardboard, or other material of suitable thickness and elasticity with a radial slit or a V-shaped notch cut in the edge of the disk 30 of paper or other material which extends radially toward the center, whereby the label may be bent or folded into a cone shaped position and then the edges placed under the crimped or bent over edges of the spool or 35 other article when the normal elasticity of the label will cause it to return to its original position and be thus retained in place. The same result may be obtained by removing a segment shaped portion from the disk 40 shaped material or label as will be fully described.

Referring to the drawings:

Fig. 1 is a sectional view partially in section of a spool of the usual construction having the ends of the spool bent or crimped over to form an annular channel and showing in dotted lines the way the label is inserted.

Fig. 2 is a plan view of the disk shaped label with a radial slit therein.

Fig. 3 is a view of the disk shown in Fig. 2 and folded into a cone shape ready for insertion into the annular channel of the spool head.

Fig. 4 illustrates the insertion of the disk

shaped label in which the edges have been cut away by removing a segment shaped portion.

Fig. 5 is a view of one of the disks showing the same with portions of its edges removed.

Fig. 6 illustrates how the label, shown in Fig. 5, is folded when it is ready for insertion.

Fig. 7 is a detail view of another form in which a V-shaped notch is cut or a portion of the material removed from the disk permitting it to be folded as shown in Fig. 2, and

Fig. 8 is a view showing its folded position.

Referring to the drawings in detail:

The barrel part of a spool for receiving wire is indicated at 1 and the end of the spool on which the label is placed is indicated at 2 having the crimped or bent over edge 3 forming the annular channel 4. This is the usual construction of the spool end or head of a metal spool. 5 designates a disk of stiff paper cardboard or other material on which the label or reading matter is printed or displayed. This disk is formed with a radial slit 6, permitting the cardboard to be bent or folded into the cone-shape indicated in Fig. 3, since the edges of the slit 6 will permit the same to pass by each other as shown in dotted lines in Fig. 2 at 6' and the direction of the folded ends is indicated by the arrows 7 as readily understood. The dotted circle line 8 shows the diameter of the cone shaped member which is, of course, less than its original diameter as shown in full lines in Fig. 2. This diameter is such that the edge of the disk may be easily moved past the turned over edge 3 and into the annular groove 4 of the head 2. The natural elasticity of the disk is such that it will automatically assume the position shown in Fig. 1 in full lines.

Referring to Fig. 5. 9 designates a disk shaped piece of stiff paper, cardboard or other material having the segment shaped portions 10 removed as indicated by the shaded lines. In order to insert this form of disk the operator folds its opposite, or diametrically located edges 11 and 12, into the bent position indicated by the dotted lines 11' and 12'. As this is less than the diameter, the piece of cardboard or other material may then be readily slipped into 110

the annular channel 4 as indicated in Fig. 4 since the removed segment portions will not interfere with the insertion. The folded piece of this disk is indicated in Fig. 6. The edges 13 and 14 of Fig. 5 appear in this figure as slightly curved in order to show the curvature or folded position of this form of label.

Fig. 7 represents another form in which 10 the disk 5 is formed with a cut out portion 15. This permits it to be folded into the cone shaped position shown in Fig. 8 similar to that shown in Fig. 3, whereby the label may be readily inserted. The size of the 16 cut-out portion may be varied of course.

From this description it will be seen that I have provided a simple way of attaching a label to the spool head or end of a metal spool or other article and one that will be 20 easily and readily replaced and other labels attached bearing the desired reading matter.

What I claim is:

1. A label member consisting of suitable elastic material which is formed with a 25 radially arranged opening to permit the label to be bent into substantially a cone shaped position for reducing its normal diameter, whereby the reduced diameter will permit the label to pass within a crimped 30 over edge of a spool end and will then expand when released and its edge will occupy the annular channel of the edge which represents the normal diameter of the label before being bent.

2. A label for the purpose described, comprising an elastic member, as cardboard or the like, having a radial slit cut therein, whereby the disk may be formed into a cone shaped position for insertion into an 40 annular channelway, as described.

3. An article of manufacture comprising a disk-shaped member which is formed with a portion of its edge removed to permit it to be bent so as to lessen its normal diameter on the edge that is not removed or cut away, whereby it may be bent and inserted into an annular channel having an overlapping edge, the normal elasticity of the disk permitting it to assume its original position after being bent and be thereby retained in the annular channel.

4. As an article of manufacture, a disk shaped member composed of elastic material and formed with a removed portion to permit it to be bent into a position which decreases its normal diameter for insertion into an opening of less diameter than its normal size, said opening having an annular recess larger than the opening, whereby when the member is moved through the opening it will regain its original size to prevent its becoming displaced from the recess.

5. As an article of manufacture, a disk shaped member composed of elastic material and designed to serve as a label and having a portion removed therefrom to permit it to be bent into a cone shape.

6. A label designed for attachment to the spool end of a metallic spool or other article having a crimped-over edge which forms an annular channel, said label being disk shape and formed with a radially arranged opening to permit it to be bent into a cone-shaped form for inserting its edge 70 into the annular channel whereby its natural elasticity will cause it to assume its original shape with its edge in the said channel and under the crimped-over edge.

WILLIAM A. PRENTISS.
